(57) **CLAIM**

The ornamental design for a facial roller, as shown and described.

DESCRIPTION

FIG. 1 is a top perspective view of a first embodiment of a facial roller;

FIG. 2 is a front view of the facial roller shown in FIG. 1;
FIG. 3 is a back view of the facial roller shown in FIG. 1;
FIG. 4 is a right side view of the facial roller shown in FIG. 1;
FIG. 5 is a left side view of the facial roller shown in FIG. 1;
FIG. 6 is a top view of the facial roller shown in FIG. 1;
FIG. 7 is a bottom view of the facial roller shown in FIG. 1;
FIG. 8 is a top perspective view of a second embodiment of a facial roller;

FIG. 9 is a front view of the facial roller shown in FIG. 8;
FIG. 10 is a back view of the facial roller shown in FIG. 8;
FIG. 11 is a right side view of the facial roller shown in FIG. 8;

FIG. 12 is a left side view of the facial roller shown in FIG. 8;
FIG. 13 is a top view of the facial roller shown in FIGS. 8 and 14;
FIG. 14 is a bottom view of the facial roller shown in FIG. 8.
The dashed lines in FIGS. 8, 9, and 11-13 are included for the purpose of illustrating a portion of the facial roller that forms no part of the claimed design.

1 Claim, 8 Drawing Sheets
